United States Patent Office

Des. 194,886
Patented Mar. 26, 1963

194,886

BOTTLE

Isamu Kuwahara, 61 Azabu Ryudo-cho, Minato-ku,
Tokyo, Japan, and Ara Vahan Simidian, 90 1-chome
Onden, Shibuya-ku, Tokyo, Japan

Filed Jan. 23, 1962, Ser. No. 68,427

Claims priority, application Japan Aug. 2, 1961

Term of patent 14 years

(Cl. D58—8)

FIG. 1 is a front elevational view of a bottle embodying our new design;

FIG. 2 is a side elevational view thereof;

FIG. 3 is a top plan view thereof;

FIG. 4 is a bottom plan view thereof; and

FIG. 5 is a fragmentary sectional view taken on line 5—5 of FIG. 2.

We claim:

The ornamental design for a bottle, as shown.
